UNITED STATES PATENT OFFICE.

HENRY J. COX AND STEPHEN J. GALLAGHER, OF NEW ORLEANS, LOUISIANA.

FULCRUM-BLOCK.

946,496.

Specification of Letters Patent.

Patented Jan. 11, 1910.

Application filed August 21, 1909. Serial No. 514,047.

To all whom it may concern:

Be it known that we, HENRY J. COX and STEPHEN J. GALLAGHER, citizens of the United States of America, residing at New Orleans, Louisiana, have invented certain new and useful Improvements in Fulcrum-Blocks, of which the following is a specification.

This invention relates to new and useful improvements in fulcrum blocks for brake beams and more particularly to a fulcrum block of that general type in which provision is made for the use of either a right-hand or a left-hand brake lever.

The primary object of the invention is to provide a fulcrum block of the general type referred to of such novel construction that fillers or liners for coöperation with the brake lever are unnecessary. Consequently the present block involves a lessening of cost and a quicker and more convenient operation of changing the inclination of the lever.

A further object of the invention is to provide a novel construction of sectional fulcrum block in which special regard is had to convenience of assemblage, strength and inexpensiveness.

In the accompanying drawings we have illustrated, by way of example, a preferred and advantageous embodiment of the invention.

In the said drawings: Figure 1 is a detail perspective view illustrating a brake beam equipped with a brake lever and fulcrum block constructed in accordance with the present invention. Fig. 2 is a vertical longitudinal section of the fulcrum block, and Fig. 3 is a cross sectional view thereof showing the pivot of the brake lever.

Similar numerals of reference designate corresponding parts throughout the several views.

The brake beam is designated by the numeral 1 and consists preferably of an I bar provided at its ends with the shices 2 which, in so far as the present invention is concerned, may be of any approved form.

The fulcrum block is designated in a general way by the numeral 3 and the brake lever by the numeral 4. The fulcrum block consists of upper and lower counterpart sections 5, each having at its rear end a recessed axially extended lug, as 7. The lugs 7 fit over opposite sides of the beam and are secured thereto by a bolt and nut or

other equivalent fastening, as 8. The sections 5 are fitted against one another and are held in such relation by the fastening 8 above mentioned, and by a similar fastening, as 9, which passes through the forward end portions of said sections.

Each section 5 is formed with a pair of longitudinal slots, 10 and 11, which extend at right angles, toward one another and register with corresponding, similarly designated slots, in the opposing section. The slots 10 and 11 in their registering relations thus afford continuous intersecting openings, each of which may receive the brake lever 4. Between the slots of each section longitudinal triangular webs, as 12, occur, which are of such proportions as to assure that the formation of the slots does not materially weaken the fulcrum block. Similar webs occur between the slots of the adjacent blocks and, while these webs are in sections, they subserve the same purpose, by virtue of the abutting relation of the sections.

The brake lever 4 is formed with an intermediate slotted opening, as 13, through which the cotter pin 14 passes. The cotter pin 14 is vertically disposed and extends through the opposed solid webs 12 and intersects the centers of the openings 10 and 11. The cotter pin 14 provides for the ready removal of the brake lever which may be fitted in either of the continuous slotted openings 10 or 11 according to whether a right-hand or a left-hand inclination is desired.

The provision of the vertically disposed pivot pin in connection with the intersecting openings provides for the use of the block indifferently with either a right-hand or a left-hand brake lever and dispenses with the use of fillers or liners or similar intermediate parts. At the same time it provides for an easy and quick changing operation, it being necessary simply to remove the pivot bolt, change the lever, and replace the bolt.

In view of the fact that the sections are counterparts, the block may be made at a minimum cost and at the same time the arrangement provides for strength just as effectually as would a solid block.

Having fully described our invention, we claim:

1. A fulcrum block for brake beams having a pair of continuous intersecting slotted openings, in combination with a brake lever for arrangement in either of the openings, the brake lever having an intermediate

opening and a pivot bolt passed vertically through the intersection of the slotted openings and through the opening in the brake lever.

5 2. A fulcrum block for brake beams comprising a pair of counterpart sections, each having a pair of openings extending toward one another, the openings of one section registering with the corresponding openings of the other section, and means for securing the sections in position against one another, in combination with a brake lever which may be pivoted indifferently in either pair of registering openings.

15 3. A fulcrum block for brake beams comprising a pair of counterpart sections, each having a pair of longitudinal slots extending toward one another and a longitudinal

triangular web between the slots, the slots of one section registering with the corresponding slots of the other section, and means for securing the sections in position against one another, in combination with a brake lever having an intermediate opening and a pivot bolt secured in the webs and passing vertically through the intersection of the slots and through the opening in the brake lever.

In testimony whereof we have hereunto set our hands in presence of two subscribing witnesses.

HENRY J. COX.

STEPHEN J. GALLAGHER.
